PACKING AND DISPLAY CONTAINER

Filed May 2, 1929

Inventor
A. J. Tanner

UNITED STATES PATENT OFFICE

ARNOLD J. TANNER, OF NORTH HAVEN, CONNECTICUT, ASSIGNOR TO EINSON-FREEMAN CO., INC., A CORPORATION OF NEW YORK

PACKING AND DISPLAY CONTAINER

Application filed May 2, 1929. Serial No. 359,734.

The present invention relates to containers employed for packing, displaying and dispensing merchandise and relates more particularly to a type of container composed of a plurality of containing sections which are folded together so that the sections lie top to top for packing purposes, and for dispensing and displaying purposes, the sections are unfolded so that one section will stand behind and above the other section.

In previously known containers of a certain class, the two sections are composed of a single blank and the sections are so hinged together that they may be placed in the two positions above referred to. In this type of box, the construction is such that the sections must stand, when set for display, in a position wherein the center of gravity is often comparatively so high that the container is apt to topple over, particularly when part of the contents are removed, so as to destroy the balance which might have existed when the container was completely filled. To obviate this disadvantage, the sections are composed of separate members united together and supported by means which will hold the sections in determinable stepped relation to each other so as to produce a tier-like effect. An invention embodying these features broadly is the subject of a companion application, Serial No. 189,773, filed May 9, 1927 and the present invention introduces additional improvements or modifications in said former invention.

According to the present invention, the improvements, amongst others, consist of the provision of means whereby the union of the two sections together is rendered more secure and is more easily effected. Furthermore, the arrangement is such that the sections are not entirely separated from one another for packing but instead, they need be only moved into relative angular and vertical positions so that the sections may be brought together with the tops thereof abutting or adjacent to each other. The sections may also be placed, one behind the other in stepped relation to each other. The former position is the one in which the sections lie when the container is packed for shipping and the latter posi-

tion is the one in which they are placed when the container is employed for displaying and dispensing merchandise.

Besides the improvements in the means of connection, additional improvements have been made in the easel or support for the sections and all of which improvements, with others, will be more fully described with reference to the accompanying drawing, wherein—

Figure 1 is a perspective view showing the complete container set up for display and dispensing purposes;

Figure 2 is a side elevation of the set up container;

Figure 3 is a plan view of the blank of which the rear section of the container is composed;

Figure 4 is a plan view of the blank of which the front section is composed, and

Figure 5 is a detail view showing a separate blank of which the easel or support for the container is composed.

Referring to said drawing, the complete container is composed of the front section 1 and rear section 2, each of these sections having the front wall 3, side walls 4 and back wall 5. The back wall of each section is extended and folded inwardly to form an inner or double back wall 6. The extension 6 of the rear section is extended above the side walls at 7 and is cut if desired to provide a cut-out display 8 arranged to stand prominently at the back of the container. The front surfaces of the side and front walls, also of the folded in back wall of both sections only are exposed, consequently, printing on only one side of the board is required throughout the container.

Both sections 1 and 2 have open fronts to receive the contents, for example, cartons 9 as shown in broken lines in Figures 1 and 2. The front wall of the rear section carries the tongue 10 shown in operative position in Figure 1 by dotted lines. This tongue 10 has expanded ends or projections 11, a notch 12 and lugs or projections 13. The back wall of the front section has a slot 14 which is formed by a single cut line as shown in the blank illustrated by Figure 4. When the

section 6 is folded inwardly, the slot is formed and at the same time, the guide lip 15 is raised. The back wall of the front section is extended downwardly to form the easel or support 16. This extension 16 is cut away to provide seats 17 between extensions 18 and 19.

In the initial assembling, the blanks shown in Figures 3 and 4 have their ends united together by means of the glue lap 20 being adhesively secured to the other end 21 of the blank. Previous to this folding or afterwards, as may be most convenient, the extension 16 is folded on the line 22 and the edge 15 of the extension 19 is glued so as to be adhesively secured to the back wall of the section carrying the same.

In the final assembling of the complete container, the two blanks are folded in a conventional manner to form two separate container sections. These sections are united together by means of the tongue 10 being inserted into the slot 14 first by a side or angular relative positioning of the tongue so that the notch 12 will permit the insertion of the expanded ends 11. The tongue 10 is of sufficient length to allow the relative displacement of the two sections so that the two sections may be brought together so that the contents will abut and in which top to top position both sections together are pushed into a sliding sleeve or the like, (not shown) to form a shipping package. The expanded ends 11 engage the stock at each side of the slot and thus prevent withdrawal of the tongue.

When it is desired to set the container up for display, the operator need only push the tongue down into the slot, beyond the projections 13 and during which operation the rear container is conveniently seated in the easel or support 16. The engagement of the projections 13 prevents the tongue from being pulled out and thereby the two sections so united are firmly secured together against displacement.

In the foregoing described example, the easel is integral with the container forming blank. In some cases an easel composed of heavier board is required, therefore, as shown in Figure 5, a modified form of easel is designed. With this example, the easel is composed of a separate blank, substantially the same as in the other instance with only the addition of a tongue 23 arranged to fold upwardly and to be inserted into the open bottom of the rear wall of the front section. In this example, the projection 10 is engaged in a slot or under a tongue which would be provided in the back wall. By means of this engagement and that of the tongue 23, the easel is separately but firmly carried by the front container section, and when opened, provides a comparatively rigid support for the complete container.

In both examples, the supporting easel

holds the two sections in a stepped or tier position as shown in Figures 1 and 2.

It will be noted the projections or stops 11 on the connecting tongue must in all instances be in the same relative position with the top edge of the container section carrying said tongue to permit end to end placement of the sections.

It will further be noted the tongue may be shortened or lengthened at its base so as to respectively raise or lower the position of the rear section and thereby change the center of gravity to meet the requirement.

Various modifications may be made in carrying out the details of the invention hereinbefore described and it is to be understood that any modification coming fairly within the terms of the appended claims shall be covered thereby.

I claim:—

1. A display box of the type having a pair of box sections hinged together, said sections standing one behind the other when the box is arranged for displaying and end to end when the box is arranged for storage characterized by means for uniting said sections, said means comprising a tongue carried by the front wall of the rear box section, said tongue being engaged in a slot located in the front box section at substantially the hinge line between the sections and said tongue having projections operating to retain said tongue in place.

2. A display box according to claim 1 having an extension of the rear wall of the front box section folded inwardly over said rear wall to conceal the portion of said tongue projecting through said slot.

3. A display box according to claim 1 having a flap hinged to the upper edge of the rear box section folded over to present a finished surface over the exposed rear wall of the rear box section.

4. A display box according to claim 1 wherein said tongue is capable of a limited sliding movement to permit adjustment of the rear box section relatively to the front box section, and means for supporting and retaining said rear section in the adjusted position.

5. A display box of the type having front and rear box sections hinged together and capable of a relative sliding movement, said sections standing one behind the other when the box is arranged for display and end to end when the box is arranged for packing and storage characterized by a tongue carried by one box section slidably engaged in a slot formed in the other box section, said tongue providing the hinge for said sections, and said tongue having engaging projections for limiting said sliding movement.

6. A display box of the type having front and rear box sections hinged together and

capable of a relative sliding movement, said sections standing side by side when the box is arranged for display and end to end when the box is arranged for packing and storage 5 characterized by a tongue carried by one box section engaged in a slot formed in the other box section, said tongue providing the hinge for said sections, said tongue having means

for limiting said sliding movement, and said means comprising projections located at the free ends and base of said tongue.

Signed at New Haven, county of New Haven, State of Connecticut this first day ⁷⁰ of May, 1929.

ARNOLD J. TANNER.
